(57) **CLAIM**

The ornamental design for a beverage dispenser, as shown and described.

DESCRIPTION

FIG. 1 is a perspective view of a beverage dispenser showing our new design;

FIG. 2 is an environmental perspective view thereof showing liquid contents;

FIG. 3 is an exploded perspective view thereof;

FIG. 4 is an exploded perspective view thereof with all removable parts shown;

FIG. 5 is a perspective view thereof with all the parts removed for ease of illustration save the transparent portion;

FIG. 6 is a front view of FIG. 1 at a reduced scale;

FIG. 7 is a left side view thereof, the right side view being a mirror image;

FIG. 8 is a bottom plan view thereof;

FIG. 9 is a top plan view thereof;

FIG. 10 is a front view of one removable portion of the beverage dispenser with all other parts removed for ease of illustration;

FIG. 11 is a side view thereof, the opposite side is a mirror image thereof;

FIG. 12 is a bottom plan view thereof;

FIG. 13 is a top plan view thereof;

FIG. 14 is a top plan view of the lid portion of the beverage dispenser with all other portions removed for ease of illustration;

FIG. 15 is a side view thereof, both sides being identical;

FIG. 16 is a front view thereof, the rear view being identical;

FIG. 17 is a top plan view of a removable support for the beverage dispenser with all other portions removed for ease of illustration;

FIG. 18 is a front view thereof, all sides being the same;

FIG. 19 is a sectional view taken along line 19-19 of FIG. 17;

FIG. 20 is a rear view of FIG. 5 at a reduced scale;

FIG. 21 is a side view thereof, the right and left sides are mirror images thereof;

FIG. 22 is a front view thereof;

FIG. 23 is a top plan view thereof; and,

FIG. 24 is a bottom plan view thereof.

Diagonal shading lines indicate transparency.

Diagonal lines in FIG. 19 are sectional indicators.

Broken lines in FIG. 2 indicate environmental boundaries of liquid contents and form no part of the claimed design.

1 Claim, 9 Drawing Sheets
